UNITED STATES PATENT OFFICE.

OTTO STERNOFF-BEYER, OF CARLSTADT, NEW JERSEY, ASSIGNOR TO THE BROOKLYN RAILWAY SUPPLY COMPANY.

RAIL-SWEEPING ATTACHMENT FOR STREET-CARS.

SPECIFICATION forming part of Letters Patent No. 438,868, dated October 21, 1890.

Application filed March 17, 1890. Serial No. 344,271. (No model.)

To all whom it may concern:

Be it known that I, OTTO STERNOFF-BEYER, a citizen of the United States, residing at Carlstadt, Bergen county, New Jersey, have 5 invented certain Improvements in Rail-Sweeping Attachments for Street-Cars, of which the following is a specification.

This invention relates to means used in connection with street, tram, or similar cars for 10 sweeping the tracks as the car moves along.

The broom or brooms, for I prefer to use two—one over each rail and on a common shaft—turn on substantially horizontal axes, and their shaft is mounted in a broom-frame 15 which is hung at its other end on the car-axle, means in the nature of a spring or the like being employed to raise and hold up the frame and to keep the brooms normally out of contact with the rails. In this broom-carrying 20 frame is pivotally mounted another supplementary or auxiliary frame, in which is rotatively mounted an auxiliary shaft, which is driven from the car-axle through the medium of gears. The brooms are rotated from this 25 auxiliary shaft through the medium of a belt or chain and sprocket-wheels. A spring or the like serves to rock the said auxiliary frame in such a manner as to disengage the driving-gears and render them inoperative and to allow 30 the broom-frame to be elevated by its spring. When the operator, by the means to be described, depresses the auxiliary frame, the first effect is to put the gears into engagement and set the brooms in motion, and then 35 to depress the rotating brooms into contact with the track. Thus the means for putting the driving-gears into and out of engagement are to some extent independent of those for depressing the brooms, and the two do not act 40 altogether simultaneously, but rather successively—that is to say, the auxiliary frame is independently depressed until the gears are in operative engagement—after which the further depression of said frame depresses 45 the broom-frame also, and when the operator allows the broom-frame to rise it rises first to its full extent and then the auxiliary frame rises independently and disengages the gears.

In the accompanying drawings, which serve 50 to illustrate my invention, Figure 1 is a plan

of a portion of the floor-frame and wheels of a street-car provided with my improvements; and Fig. 2 is a sectional elevation of the same, the plane of the section being indicated by the broken line $x x$ in Fig. 1.

55

a represents the floor-frame of the car, b the axles, and c the wheels. The wheels run on track-rails d . On a transversely-arranged shaft e are fixed two circular brooms f , one over each track-rail. These brooms may be 60 constructed in the same manner as brooms usually used in street-sweepers, or in any suitable manner. The shaft e is rotatively mounted in the ends of two arms g , which are mounted to turn about one of the axles b at 65 g' . Mounted in these arms near the axle is a rock-shaft h , on which are secured two arms i , in which is rotatively mounted a shaft j , on which is fixed a pinion k , adapted to gear with a toothed wheel l on the car-axle. The 70 broom-shaft e is driven from the shaft j through the medium of sprocket-wheels m on the respective shafts and a chain belt n . Fixed to the boss of one of the arms i , or it may be 75 fixed to the rock-shaft h independently of said arms, is an upwardly-projecting arm o , to which is attached one end of a disengaging-spring p , the other end of which is secured to the car. This spring (a portion only 80 of which is shown in Fig. 1) tends always to rock the shaft h and throw the pinion k out of gear with the wheel l on the car-axle, and thus to stop the rotation of the brooms. Another spring q , attached at one end to the 85 rock-shaft h and at its other end to the car, tends always to overcome the weight of the brooms and raise them off from the track-rails.

The brooms are pressed down upon the track-rails and the toothed wheels held in 90 gear by means of a rod, chain, or other like connector r , which is attached at one end to the arm o , and at the other end to the one arm of a horizontal lever s , pivotally mounted under the car. From this lever another connector r' extends to the platform of the car, passes thence about a guide-sheave, and up through the platform, where it is provided with a ring to engage a hook t on the dashboard. When this connector r' is drawn 95 100

taut and hooked fast, the shaft *h* is rocked, the pinion *k* put into gear with the wheel *l*, and the brooms depressed until they bear on the rails. The rocking of the shaft *h* is limited by arms *u* fixed thereon, the laterally-bent ends of which are provided with stout set-screws, which impinge on the respective arms *g*, and thus depress said arms and the brooms carried thereby when the connector 10 *r'* is drawn taut, as represented in Fig. 2. The set-screws in the arms *u* are not essential; but they serve to regulate with accuracy the extent to which the teeth of the pinion *k* may enter between the teeth of the wheel *l*.
 15 The arms *g* constitute what I have called the "broom-frame," and the rock-shaft *h* and arms *i* constitute what I have called the "auxiliary frame." The shaft *h* being situated between the broom-shaft and the car-20 axle, it follows that when the auxiliary frame shall have been rocked until the pinion *k* is in gear with wheel *l* and the set-screws in the arms *u* rest on the broom-frame then any further depression of the auxiliary frame 25 will cause it and the broom-frame to move together.

Very little force will be needed to draw the connector *r'* taut, and it may be applied in any desired manner, and when drawn taut 30 may be secured in any convenient manner. When the connector is disengaged, the spring *p* disengages the driving-gears, and the spring *q* raises the brooms clear of the rails. The spring *p* need not be very strong and the 35 power of spring *q* need only be a little in excess of that required to counterbalance the weight of the brooms and their appurtenances.

It will be obvious that the connectors *r* and 40 *r'* may be one or continuous, and that the device may be operated from one end of the car only; but I have shown the lever *s* provided with two operating rods, chains, or 45 connectors *r'* and *r''*, coupled to its respective ends and extending to opposite ends of the car, respectively. This enables the sweeping mechanism to be put in operation from either end of the car at will. However, the lever *s* and connector *r''* may be omitted 50 and the connectors or rods *r* and *r'* be continuous, as before stated. If the lever *s* be employed, its pivot bolt or pin *v* may be extended down to the proper distance to serve as a stop to limit the upward movement of 55 the broom-shaft, as indicated in dotted lines in Fig. 2.

Whichever way the car is run the brooms turn in a direction opposite to that of the wheels of the car.

60 Fig. 2 shows the floor of the car in section; but the floor is omitted from Fig. 1, in order to show the mechanism beneath it.

Having thus described my invention, I claim—

65 1. In a rail-sweeping attachment for cars, the combination, with a broom-frame pivoted on the car-axle, and a rotatively-mounted

broom carried by said frame, of a gear-wheel on the axle for driving said broom, a rocking auxiliary frame pivoted in the broom-frame, 70 an auxiliary shaft in said rocking frame geared to the broom-shaft, and a pinion on said auxiliary shaft adapted to be thrown into and out of engagement with the gear-wheel on the axle by the rocking of said auxiliary frame, substantially as set forth. 75

2. The combination, with a car having wheels and axles, of a broom-frame pivoted on the car-axle, means for automatically raising said frame and keeping it normally elevated, a rotary broom mounted in bearings on the broom-shaft and adapted to be raised and depressed therewith, an auxiliary rocking frame pivotally mounted in the broom-frame and having in it a shaft coupled to the broom-shaft, reciprocal gearing on the car-axle and the shaft in the auxiliary frame, which is made operative by the depressing of said auxiliary frame to transmit motion from the axle to the broom-shaft and inoperative by 80 the elevation of said auxiliary frame, and means for first depressing said auxiliary frame until the broom is set in motion, and then depressing the two frames simultaneously, substantially as set forth. 85

90 3. In a rail-sweeping attachment, the combination, with the car-axle provided with a toothed wheel *l*, of the swinging arms *g*, the broom-shaft mounted in said arms *g*, the sprocket-wheel on said broom-shaft, the brooms on said broom-shaft, means, substantially as described, for holding said brooms normally away from the track-rails, the shaft *j*, rotatively mounted in the arms *i*, the pinion *k*, mounted on shaft *j* in position to engage 95 the toothed wheel *l* on the car-axle, the sprocket-wheel *m* on said shaft *j*, the endless belt about the sprocket-wheels *m m*, whereby the broom-shaft may be driven from shaft *j*, means, substantially as described, for holding 100 pinion *k* normally out of engagement with toothed wheel *l*, and means, substantially as described, for forcing said pinion into engagement with the toothed wheel on the car-axle, whereby the brooms are pressed down 110 upon the track-rails and the gears put into engagement simultaneously, substantially as set forth. 115

4. In a rail-sweeping attachment, the combination, with the car-axle provided with the toothed wheel *l*, of the swinging arms *g*, the broom-shaft rotatively mounted in said arms *g* and provided with a sprocket-wheel *m*, the brooms on said shaft, means for holding said brooms normally away from the track-rails, 120 the rock-shaft *h*, mounted in arms *g*, the arms *u* on said rock-shaft and bearing on the arms *g*, the rock-arms *i* on shaft *h*, the shaft *j*, rotatively mounted in arms *i*, the pinion *k* on said shaft *j*, in position to engage the toothed 125 wheel *l* on the car-axle, whereby said shaft *j* may be driven therefrom, the sprocket-wheel *m* on shaft *j*, the endless belt about wheels *m m*, whereby the broom-shaft may be driven 130

from shaft *j*, and means, substantially as described, for holding said pinion *k* out of engagement with the toothed wheel *l* on the car-
5 axle normally, and means, substantially as described, for rocking shaft *h*, whereby the brooms are pressed down upon the rails and the gears put into engagement simultaneously, substantially as set forth.

In witness whereof I have hereunto signed my name in the presence of two subscribing to witnesses.

OTTO STERNOFF-BEYER.
